UNITED STATES PATENT OFFICE.

GLENN S. WILLIAMSON, OF NEW YORK, N. Y.

PRINTING-PRESS.

1,104,461.

Specification of Letters Patent. Patented July 21, 1914.

Application filed November 3, 1911. Serial No. 658,302.

To all whom it may concern:

Be it known that I, GLENN S. WILLIAMSON, a citizen of the United States, and residing in the borough of Manhattan, county 5 and State of New York, have invented certain new and useful Improvements in Printing-Presses, of which the following is a specification.

This invention relates to multiple rotary web printing presses, and more particularly to improvements in mechanism for assembling the printed sheets in newspaper form.

The object of the invention is to effect a very great reduction in the amount of waste due to the tearing of the webs, to avoid the consequent serious loss of time, to reduce the labor and attention incident to the running of the press, and to improve the appearance of the product by removing the cause of the 20 smutting of the pages which is often observable.

In modern multiple rotary web printing presses the sheets may be assembled entirely in book-fold, that is with all of the longitudinal-folded sheets nested together, or the newspapers may be formed of sections placed together, each section comprising a plurality of sheets in book-fold. For some purposes it is more desirable to book-fold, and for others it is more desirable to form sections. In general, it is very desirable to have all of the sheets assembled in book-fold, because this avoids possible subsequent loss of part of the paper; but this mode of assembling has a very serious drawback, in that it calls for the utilization of numbers of angle-bars. In book-folding as now practised in multiple rotary web presses the double-width webs are slit longitudinally, and the course of the so-produced single-width webs at one side must be changed so as to cause them to travel in superposed relation to the others. The single-width webs are thus brought all together, so that they 45 may be passed over a longitudinal folder to be nested together in book-fold; but the changing of the courses of the halves of the webs at one side necessitates the use of a number of angle-bars, two for each sheet so 50 transposed. As is well-known, these are immovable bars positioned at an angle to the longitudinal edges of the single-width webs, over which the webs must be drawn with considerable strain and friction. From the 55 very nature of things these angle-bars are constant seats of trouble. Should the slit-

ters become dull, or if for any other reason the edges of the slit webs are rough, one or more of the webs will tear across at the angle-bar; and weak spots or slime marks in the paper will produce the same result. The tearing of a web necessitates, of course, the stopping of the press. It also necessitates the tearing away of the affected web and the re-threading of the paper. It is often necessary, also, to tear away a number of the webs above or below the web affected; and, in any event the material of all the webs beyond the region of a break in one of them is waste, because it could only produce incomplete papers. In addition to this the broken sheet may have to be torn diagonally, or feathered, for many feet in rear of the break, in order to thread it through the press again, and this is waste not only in this sheet, but in all the other sheets, because their corresponding parts must be discarded as incomplete papers. The whole operation involves the waste of a large amount of material and a serious loss of time. Because the consequences of the tearing of a web at an angle-bar are not limited to that web alone, the total waste due to angle-bars amounts to a large sum and is very costly to the printing plant. Moreover, the angle-bars are likely to spoil the appearance of printed webs by smearing of the comparatively fresh ink, because as the webs pass over the bars the latter collect more or less of the ink from the surfaces and redistribute it over the succeeding portions of the webs.

In accordance with my invention I do away with angle-bars. I combine a plurality of sets of printing couples for printing a plurality of webs, and two longitudinal folders in series, with slitting mechanism, and with means for associating and leading all the webs to the first longitudinal folder, where the two longitudinal halves of all the double-width webs are folded or doubled over on each other, after which the assemblage of superimposed single-width webs are conducted over the second former, where they are again folded longitudinally. After this the book-folded product is folded and cut transversely and delivered by suitable mechanism. Preferably a single slitting mechanism is provided for slitting all the double-width webs simultaneously. In the best embodiment of the invention, the slitting means is located in advance of the first

former, and compensating means is interposed between the slitting means and the first former for causing the heads of pages on the two longitudinal halves of the slit webs to come into front register, it being customary to print the pages of the two halves in staggered relation. Forwarding mechanism is provided between the two longitudinal folders. The first longitudinal folder with its former is double-width; the second longitudinal folder is preferably smaller, being single-width. Thus, I superimpose and simultaneously fold or double over the plurality of webs upon each other longitudinally, slitting them at an appropriate point or points, and then again fold the so-produced assemblage of superimposed single-width webs longitudinally to produce the book-fold. The double-width webs are slit longitudinally, the single-width webs are then compensated, next the slit webs, still traveling double-width, are superimposed and folded over upon each other longitudinally, after which the assemblage of superimposed single-width webs are folded longitudinally.

A further object of the invention is to enable the press either to book-fold its entire product or to associate it in sections to be gathered together, by means of a plurality of longitudinal folders and without the use of angle-bars. In the preferred construction I provide means for changing the relative position of the two folders already referred to so that the second folder may receive one longitudinal half of the webs direct, instead of receiving all of the half webs in superimposed condition from the large folder. Preferably, the second folder is rotatably mounted or swiveled so that it may be turned through an arc of approximately 90°, from one operative position to the other. In one position it is at right angles to the large former so as to operate in series therewith. In the other position it is in line with the direct run of one longitudinal half of the webs. In the embodiment of the invention illustrated, I employ three longitudinal folders, a large or double-width longitudinal folder in front of and central with respect to the other two longitudinal folders. Of these two longitudinal folders the one is rotatably mounted, so that it may be positioned either in series with the large longitudinal folder or in parallel relation to the third folder. In the first instance the mechanism is arranged for book-folding. In the second instance the two longitudinal halves of the webs, after slitting, run direct over the two parallel folders, so that the sheets are assembled in sections, which sections, placed side by side, complete the newspaper.

In the accompanying drawings illustrating the invention by means of the preferred

embodiment thereof: Figure 1 is a rear elevation, parts being broken away, of an assembling mechanism embodying my invention, the same being shown as arranged for book-folding; Fig. 2 is a side elevation of the rear part of a printing press with the assembling mechanism, parts being in section and broken away; Fig. 3 is a plan view, parts being broken away; Fig. 4 is a side elevation, with parts in section and broken away, showing the mechanism shifted for assembling the papers in sections; Fig. 5 is a sectional plan view, with parts broken away and in section, corresponding to Fig. 4; Fig. 6 is a rear view corresponding to Figs. 4 and 5, parts being broken away; and Fig. 7 is a detail view. The webs are shown in all the views.

A indicates the portion of the press frame carrying the printing couples, and A¹ the frame of the folding or assembling mechanism, between which, as is customary, there may be a passage-way. The press is provided with a plurality of sets of printing couples, one set for each web. The printing couples and their adjuncts may be of any suitable form and arrangement, and the printing mechanism is, therefore, not illustrated in detail. I have indicated a sextuple press, for purposes of illustration, there being three sets of printing couples. Each set is shown as comprising two couples, each couple consisting of a plate or printing cylinder P and an impression cylinder I. As is usual, the plates on each plate cylinder are in staggered relation. The double-width webs, a, b, c, (three being shown for purposes of illustration) are led to the printing couples and the printing is effected in the usual or any approved manner.

Fig. 2 indicates the great saving in floor space that may be effected by my invention, by the shortening of the press, as the printing couples can be located as near the rear end of the press as may be desired, all the space formerly devoted to angle-bars being unnecessary.

The plurality of double-width webs, either before or after printing, are slit longitudinally. Preferably, the webs are slit simultaneously and at one point, after printing, by means of a single slitter. The slitter 10 may be located at any suitable point, but I attain certain advantages by mounting it on the rear end of the frame A. The full-width webs a, b, c, are slit by being passed together between the slitter 10 and the roller 11. The slitter 10 may be either driven or idle, and its pressure may be regulated by means of a screw 12 acting on a spring in the usual manner. I provide means for compensating for the staggered relation of the printed pages on the two longitudinal halves of the slit webs. I pre-

fer to locate this means at a suitable point between the slitting means and the first longitudinal folder F. For the purpose of illustration I have shown a roller 13 carried by an arm 14 pivoted on the frame A, which may be adjusted by means of a screw 15. One-half of the webs passes around the roller 13, which is adjusted as the circumstances may require. Figs. 2 and 3 show the compensator acting on one longitudinal half of all the webs.

At the top of the assembling mechanism is a double-width longitudinal folder F. The same comprises a triangular former or internal guide 16 and external turners or rollers 17 at the point thereof. The former is of any suitable or approved construction. At its top is a forwarding roller 18 with which coöperate trolleys 19; and below the rollers 17 is a pair of gripping-rollers 20. The folder F is centrally in line with the direct run of the webs; by which I mean that the webs reach the top of the former 16 without lateral transportation.

Means, the specific character of which may be varied, are provided for associating and leading all of the plurality of webs from the plurality of sets of printing couples to the first longitudinal folder F. In the particular construction illustrated, the double-width webs a, b, c pass separately from their printing couple over adjustable register rollers d, e, f, and thence pass together over the roller 11 and beneath the slitter 10. The single-width webs are then compensated as described, and the slit webs, still traveling double-width, are led together between the forwarding-roll 18 and the coöperating trolleys 19.

Beyond the longitudinal folder F are two other longitudinal folders F¹ and F², these folders being preferably of single width and arranged at opposite sides of the center line of the folder F. The folder F¹ comprises a triangular former 16^a and external turners 17^a, in addition to which I have illustrated the gripping or fold-laying rollers 20^a. Between the longitudinal folders F and F¹ I provide forwarding means, the same being shown as comprising a driven forwarding-roller 18^a and trolleys 19^a, at the top of the folder F¹. In like manner the longitudinal folder F² has an internal guide or former 16^b, the external turners 17^b, and the fold-laying rollers 20^b; and a forwarding-roller 18^b and trolleys 19^b are located at the top of its former.

One or both of the longitudinal folders F¹, F² is movable between two positions, as will be presently described. Preferably, the longitudinal folder F¹ is alone so movable, the longitudinal folder F² being fixed in position in line with the direct run of one longitudinal half of the webs. The other longitudinal folder F¹ may be positioned

either in line with the direct run of the other longitudinal half of the webs, that is to say, in parallel relation to the longitudinal folder F², or in series relation to the double-width folder F. In Figs. 1, 2 and 3, the longitudinal folder F¹ is shown in series with the longitudinal folder F; in Figs. 4, 5 and 6 it is shown in parallel with the longitudinal folder F². Between the two longitudinal folders F¹ and F² compensating means is provided, for insuring that, when these longitudinal folders are in parallel relation, as shown in Figs. 4, 5 and 6, and the product of one side is led across to the other to be transversely folded and cut therewith, the pages of the two sections will be substantially in registry, so that the cutting knives will always operate in the transverse unprinted strips between pages. For this purpose I have illustrated a roller 96, carried by an arm 96 pivoted to the frame A² and adapted to be adjusted by a screw 97.

The longitudinal folder F¹ is preferably mounted rotatably, so as to turn through an arc of 90°. To this end I have shown the frame or supporting structure A¹ for the longitudinal folder F¹ swiveled on a substantially-central vertical pivot P. Sufficient clearance is provided between the frame A¹ and the parts carried thereby and the frame part A² of the longitudinal folder F² and the parts carried thereby, to permit of the rotation of the left-hand longitudinal folder. As convenient means for effecting the turning of the longitudinal folder F¹ I have shown a stationary arcuate rack 30, with which engages a pinion 31 (see Fig. 2) on the lower end of a shaft 32 journaled in the frame A¹, a handle crank 33 being provided at the upper end of the shaft and connected therewith by bevel gears 34; or any other suitable means may be employed. The forwarding mechanism, shown as comprising the forwarding-roller 18^a and the trolleys 19^a are mounted to turn with the longitudinal folder F¹. In the particular construction illustrated, the roller has a journal extension at one end received in a bearing 90 on the swiveled frame, and toward the other end is provided with an annular groove which is received in a bearing 91 on the same frame. The trolleys 19^a are carried by arms pivoted on a shaft 92 carried by brackets 93, 94 on this frame. As is usual, these and all the other trolleys are preferably provided with adjustable spring pressure devices.

The swiveled frame part A¹ also carries transverse folding and cutting mechanism and delivery devices, which may be of any suitable or usual construction, and are therefore not illustrated in detail. Briefly described these parts comprise a cutting cylinder 35, a folding cylinder 36, folding rollers 37 between which the papers are forced

by any suitable form of tucking blades carried by the folding cylinder, a rotary fly 39, and delivery tapes 40. Such devices are so well-known to those skilled in the art that 5 further description here is unnecessary. In Fig. 2 the fly 39 and tapes 40 are shown arranged to deliver into the passage-way between the press-frame and the associating mechanism, but it will be obvious that they 10 may be arranged to deliver in the opposite direction if desired. In like manner, similar parts are provided in conjunction with the longitudinal folder F², there being a cutting cylinder 35^a, a folding cylinder 36^a, 15 folding rollers 37^a, a fly 39^a and delivery tapes 40^a.

In accordance with the invention means are provided for driving the rotary parts carried by the frame portion B¹ in either of its two 20 positions. Such means may be widely varied; and, in fact, the various arrangements of gearing shown throughout are merely for the purpose of indicating the existence of driving connections, the particular arrangement of which is only a matter of mechanical skill.

41 indicates a shaft which may be regarded as the main driving shaft. It carries a bevel gear 42 which meshes with another 25 bevel gear 43, the latter being mounted on a shaft 44, which carries a gear 45. A train of gears 47 mounted on the frame A¹ is driven from this gear 45. On the shaft 48 of the topmost gear of the train is a bevel 30 gear 49, which meshes with another bevel gear 50 on the end of the journal extension of the forwarding-roller 18^a of the longitudinal folder F¹. The trolleys coöperating therewith may or may not be driven, and 35 the same applies to all the trolleys employed. The lowermost gear 47^a of the train 47 is a slip-gear, being capable of longitudinal movement of the shaft to disengage from the gear 45; as is indicated by 40 dotted lines in Fig. 1. This permits the longitudinal folder F¹ to be swung around to the position shown in Figs. 4, 5 and 6, where the gear 47^a meshes with a gear 51 mounted on the main driving shaft 41. The 45 cutting cylinder 35 is shown as being driven by means of a gear on its shaft meshing with a gear 47^b of the train 47; and the folding cylinder 36 is shown geared to the cutting cylinder 35. The folding rollers 37 are preferably geared together and one of them may be geared to the fly 39 by means 50 of an intermediate gear. The driving connections for the fly 39 and the tapes 40 may consist of two gears 52, one of which 55 meshes with the gear 47^a, while the other meshes with a gear on the shaft of the fly and a pinion on one of the shafts of the delivery tapes. The fold-laying rollers 20^a may be geared together and may be driven 60 from the folding cylinder 36 by means of a

gear 53. As has been observed, the gearing may be rearranged in any suitable way.

The gearing for driving the rotary parts carried by the frame portion A², the same including the forwarding-roller 18^b and 70 fold-laying rollers 20^b of the folder F², the cutting cylinder 35^a, the folding cylinder 36^a, the folding rollers 37^a, the fly 39^a and the delivery tapes 40^a, may be similar to that shown in connection with the parts carried by the frame portion A¹; or any suitable form of gearing may be employed. Gear connections, somewhat different from those described in connection with the parts at the left-hand side of the machine are 80 illustrated, but are not described, because they will be obvious and because the invention is not concerned with any specific arrangement of gearing. The gearing at the right-hand side of the machine is shown as 85 driven from a bevel gear 98 on the shaft 44, this gear meshing with another bevel gear 99, which is secured to the same shaft as a gear, indicated at 100, meshing with the gear 101. 90

The forwarding-rollers 18^a and 18^b are so arranged as to be in alinement when the longitudinal folders F¹ and F² are in parallel relation, as shown in Figs. 4, 5 and 6. The forwarding-roller 18^b is illustrated as 95 mounted in bearings 90^a and 91^a, similar to the bearings 90 and 91 of the roller 18^a. The bearings 91 and 91^a are so formed as to be no higher than the rollers 18^a and 18^b, so as to offer no obstacle to the passage of the 100 webs thereover. Trolleys 19^b are provided in conjunction with the roller 18^b, and are in alinement with the trolleys 19^a in this position of the parts. They are shown as similarly carried by arms mounted on a 105 shaft 92^a mounted in brackets 93^a, 94^a. Suitable clearance is provided between the rollers 18^a and 18^b with their bearings and between the trolley shafts 92 and 92^a with their brackets, so as to permit the swiveled 110 structure including the longitudinal folder F¹ to turn. When the longitudinal folders F¹ and F² are acting together in parallel to turn out sections to be assembled side by side to form the newspaper, I prefer to effect the longitudinal slitting of the webs at the rollers 18^a and 18^b, which then act like one roller. To this end I have provided the 115 adjustably-spring-pressed slitter 102, which may be either driven or not, as preferred, 120 the same being shown for purpose of illustration as mounted on an arm carried by the trolley shaft 92 and coöperating with a groove in the extension of the forwarding-roller 18^a to the right of the bearing 91. 125 This slitter is preferably mounted centrally of one of the trolleys 19^a (see Fig. 7). When the longitudinal folders F¹ and F² are in parallel, the forwarding-rollers 18^a and 18^b may obviously either be coupled 130

together so that 18^b is rotated by 18^a, or driving means may be provided for each roller. For purposes of illustration I have indicated driving connections for the roller 18^b. For this purpose I have illustrated a bevel gear 103 on the journal extension of the roller 18^b, this gear meshing with a bevel gear 104 on a horizontal shaft 105. This shaft carries another bevel gear 106, which is driven by a bevel gear 107 on a shaft 62, hereinafter referred to. It will be understood that the driving connections for the two rollers 18^a and 18^b will be so proportioned that these rollers will be driven in synchronism.

The forwarding-roller 18 and the gripping-rollers 20 of the double-width folder F may be driven in the following manner: A bevel gear 57 mounted on the shaft 41 meshes with a bevel gear 58 on a transverse shaft 59 which extends across the machine. At the opposite end of this shaft 59 is a bevel gear 60, which meshes with a bevel gear 61 on the lower end of an upright shaft 62. At the upper end of the shaft 62 is a bevel gear 63 which meshes with a bevel gear 64 on a horizontal shaft 65 and this horizontal shaft 65 has a gear 66, which meshes with a pinion 67 on the journal extension of the forwarding-roller 18. The horizontal shaft 65 extends inward to the center line of the machine and is provided at its inner end with a bevel gear 68 which meshes with a bevel gear 69 on the upper end of a vertical shaft 70, the lower end of which is provided with a bevel gear 71 meshing with a bevel gear 72 on the end of one of the gripping-rollers 20, the two gripping-rollers being geared together.

In operation, for book-folding, the longitudinal folder F¹ is positioned and the webs coming from the several sets of printing couples are threaded as shown in Figs. 1 to 3. The webs are slit centrally at any suitable point, as by means of the slitter 10. The webs pass over the former 16 and the severed longitudinal halves are folded or doubled over between the pairs of rollers 17 and 20. The superimposed half webs now pass over the former 16^a and are folded between the turners 17^a and the fold-laying rollers 20^a; after which the sheets, now in book-fold, are folded transversely, cut, and delivered in any usual or approved manner, as by means of mechanism such as illustrated for the purpose. In order to assemble the sheets in sections to be placed side by side to form the newspaper, the longitudinal folder F¹ is swung through an arc of 90° so as to be positioned as shown in Figs. 4 and 5. The slit webs are now brought down in the space between the frames A and A¹, and may be led under a guide roller 75 on the frame A¹, whence the webs pass directly to the aligned forwarding-rollers 18^a and 18^b.

of the two longitudinal folders F¹ and F² now operating in parallel. The slitter 10 is preferably placed out of operation, as by being held up; and the compensating roller 13 is also preferably not now in use. The webs are slit by the slitter 102, and the single-width webs pass half over the former 16^a and half over the former 16^b, and then between the rollers 17^a and 20^a, and 17^b and 20^b. The two longitudinal folded sections thus formed may be collected in any approved manner. Fig. 6 shows the product from the longitudinal folder F² carried transversely across, by way of the compensator 95, between the rollers 20^a with the product from the longitudinal folder F¹, the combined product being then transversely folded and cut and delivered by the transverse folding and cutting mechanism and delivery beneath said longitudinal folder F¹. In like manner, the product from the longitudinal folder F¹ may be led across to the other side, and the sections transversely folded and cut and delivered at the right-hand side of the machine.

While I have shown two complete transverse folding and cutting and delivery mechanisms, in conjunction with the two longitudinal folders F¹ and F², it will be obvious that these parts shown in conjunction with the longitudinal folder F² may be omitted, the cutting cylinder 35, folding cylinder 36, folding rollers 37, fly 39 and delivery tapes 40, or other suitable form of mechanism, being used both for book-folding and for operating on collected sections, as shown. Or, if two complete mechanisms of this character are used, as illustrated, the parts 35, 36, 37, 39 and 40 need not be mounted so as to turn with the longitudinal folder F¹, since the corresponding parts at the right of the machine may be used exclusively when the longitudinal folders F¹ and F² are operating in parallel.

I have shown a guide roller 110, carried by pivoted arms or hangers 111, which may be swung down below the rollers 20^a, as shown in Fig. 1, when the longitudinal folders F¹ and F² are at right angles to each other and acting in series. This roller may be swung up out of the way when the longitudinal folders F¹ and F² are in parallel (see Fig. 7). This roller may, however, be dispensed with.

While I have shown and particularly described one embodiment of my invention, it will be understood that many other embodiments are possible and that many changes may be made without departing from the scope of the invention.

What I claim as new is:

1. In a rotary web printing press, the combination of a plurality of sets of printing couples, web slitting means for severing said webs longitudinally, first and second longi-

tudinal folders adapted to operate in series with each other, the first folder of double width, each folder including a triangular former, a third longitudinal folder beyond the double width folder, means for associating and conducting a plurality of webs from said sets of printing couples double width directly to the first longitudinal folder without the use of angle bars and means for 10 associating and conducting a longitudinal portion of one or more webs directly to said third folder.

2. In a rotary web printing press, the combination of a plurality of sets of printing 15 couples, web-slitting means for severing said webs longitudinally, first and second longitudinal folders adapted to operate in series with each other, the first folder of double width, each comprising a triangular former 20 and rollers at the point thereof, forwarding means between the longitudinal formers, a third longitudinal folder beyond the double width folder, means for associating and conducting a plurality of webs from said sets 25 of printing couples double width directly to the first longitudinal folder without the use of angle bars and means for associating and conducting a longitudinal portion of one or more webs directly to said third folder.

3. In a rotary web printing press, the combination of a plurality of sets of printing couples, web-slitting means, two longitudinal folders adapted to operate in series with each other, one of double width, each comprising 35 an internal former and external turners, compensating means between the slitting means and the first longitudinal folder, a third longitudinal folder beyond the double width folder, means for associating and conducting a plurality of webs from said sets 40 of printing couples double width to the first longitudinal folder, including a registering roller for each web and a guide roller over which the associated webs pass on their way 45 to the first longitudinal folder and means for associating and conducting a longitudinal portion of one or more webs directly to said third folder.

4. In a rotary web printing press, the combination of a plurality of sets of printing 50 couples, a single slitting means for slitting all the double-width webs of said sets simultaneously, two longitudinal folders adapted to operate in series with each other, one of 55 double width, each comprising an internal former and external turners, a third longitudinal folder beyond the double-width folder, a slitter in advance of said third folder, means for associating the plurality of 60 webs from said sets of printing couples and conducting them by way of the single slitting means to the first longitudinal folder by which the plurality of slit double width webs is folded longitudinally to be again 65 folded longitudinally into book-fold by the

second folder and means for associating and conducting a longitudinal portion of one or more webs directly to said third folder.

5. Mechanism for folding the product of a printing press, comprising two longitudinal folders in series, one of them of double width, each comprising a triangular former and rollers at the point thereof, forwarding mechanism between said folders, a third longitudinal folder beyond the double width folder and means for leading webs either to said double width folder directly without the use of angle bars or a portion of the webs printed by the press directly to said third folder. 70

6. Mechanism for folding the product of a printing press, comprising means for slitting the double width web, two longitudinal folders in series, one of them of double width, each comprising an internal former and external turners, compensating means between the slitting means and the first longitudinal folder, a third longitudinal folder, beyond the double-width folder, and means for leading webs either to said double width folder directly without the use of angle bars or a portion of the webs printed by the press directly to said third folder. 75

7. In a printing press, a folding and associating mechanism, comprising a plurality of longitudinal folders in series each including an internal former, the first of the folders of double width, a third folder beyond said first folder and means for leading webs either to said double width folder directly 80 without the use of angle bars or portions of the webs printed by the press directly to said second and third folders. 95

8. In a printing press, a folding and associating mechanism, comprising a plurality of longitudinal folders each including an internal former, and means for moving one of said longitudinal folders whereby they may operate either in series for book-folding or in parallel for producing sections to be 100 gathered together. 105

9. In a folding mechanism for printing presses, the combination with a longitudinal folder, and another longitudinal folder, of a third longitudinal folder mounted so 115 as to be movable either into series relation to the first named folder or into parallel relation to the other longitudinal folder.

10. In a folding mechanism for printing presses, the combination with a longitudinal folder, slitting mechanism, and another longitudinal folder, of a third longitudinal folder mounted so as to be movable either into series relation to the first named folder or into parallel relation to the other longitudinal folder. 120

11. In a folding mechanism for printing presses, the combination with a double-width longitudinal folder, and a single-width longitudinal folder, of a third single- 125 width longitudinal folder. 130

- width longitudinal folder movable either into series relation to the double-width longitudinal folder or into parallel relation to the other single-width longitudinal folder.
- 5 12. In a folding mechanism for printing presses, the combination of two triangular formers disposed side by side, and a triangular former in advance of and central with respect to said formers, one of said two formers being mounted so as to be movable either into series relation to the central former or into parallel relation to the other former. 70
- 10 13. In a folding mechanism for printing presses, the combination with a primary longitudinal folder and another primary longitudinal folder, of a third longitudinal folder rotatably supported so as to serve either as a secondary longitudinal folder in series with the first named longitudinal folder or as a primary longitudinal folder in parallel with the other longitudinal folder. 75
- 15 14. Folding mechanism for a printing press, comprising the combination of a longitudinal folder centrally in line with the direct run of the webs and comprising a former and external turners, a narrower longitudinal folder in line with the direct run of one longitudinal half of the webs and comprising a former and external turners, another narrower longitudinal folder, and a rotatable support therefor enabling it to be positioned either in line with the direct run of the other longitudinal half of the webs or in series with the first named longitudinal folder at right angles thereto. 80
- 20 15. Folding mechanism for a printing press, comprising the combination of a longitudinal folder centrally in line with the direct run of the webs and comprising a former and external turners, slitting mechanism, a narrower longitudinal folder in line with the direct run of one longitudinal half of the webs and comprising a former and external turners, another narrower longitudinal folder, and a rotatable support therefor enabling it to be positioned either in line with the direct run of the other longitudinal half of the webs or in series with the first named longitudinal folder at right angles thereto. 85
- 25 16. Folding mechanism for printing presses, comprising a double-width longitudinal folder, and a second longitudinal folder mounted movably so as either to operate in series with the double-width longitudinal folder or to receive one longitudinal half of the webs direct. 90
- 30 17. In a folding mechanism for printing presses, the combination with a double-width longitudinal folder comprising a former and external turners, of another longitudinal folder also comprising a former and external turners, and a rotatable support for the latter folder enabling it either 95
- 35 to be positioned at right angles to the double-width longitudinal folder so as to operate in series therewith or to be turned into line with the direct run of one longitudinal half of the webs. 100
- 40 18. Folding mechanism for printing presses, comprising three longitudinal folders each comprising a triangular former and rollers at the point thereof, one of said longitudinal folders being double-width and in advance of the other two, and means whereby one of these may be moved either into series relation to the double-width longitudinal folder or into parallel relation to the third longitudinal folder. 105
- 45 19. Folding mechanism for rotary web printing presses including two longitudinal folders each comprising a triangular former and external turners, and means whereby the relative position of the longitudinal folders may be changed so that one of them may either operate in series with the other or receive one longitudinal half of the webs direct. 110
- 50 20. In a folding mechanism for rotary web printing presses, a longitudinal folder comprising a triangular former and external turners, and a rotatable support for said longitudinal folder, substantially as set forth. 115
- 55 21. In a folding mechanism for rotary web printing presses, a longitudinal folder including an internal triangular former and means whereby said folder may be moved from a position lengthwise of the press to a position substantially at right angles thereto. 120
- 60 22. In a folding mechanism for rotary web printing presses, the combination of a longitudinal folder, transverse cutting and folding mechanism, and a rotary support for the whole whereby the apparatus may be turned through an arc of 90° as and for the purposes set forth. 125
- 65 23. In a folding mechanism for rotary web printing presses, the combination of a longitudinal folder comprising a triangular former and rollers, a swiveled support for the longitudinal folder whereby it may occupy either of two operative positions, driving means outside of the swiveled support, and means whereby the rollers may be driven thereby at either position of the folder. 130

25. In a folding mechanism for rotary web printing presses, the combination of a double-width longitudinal folder, two other longitudinal folders, one of which is movable to be positioned either in parallel relation to the other or in series relation to the double-width folder, and slitting mechanism from which the half webs may be led directly either to the double-width longitudinal folder or to the other two longitudinal folders in parallel.

26. In a folding mechanism for rotary web printing presses, the combination of a double-width longitudinal folder, two other longitudinal folders, one of which is movable to be positioned either in parallel relation to the other or in series relation to the double-width longitudinal folder, and slitting and compensating mechanism from which the single-width webs may be led

directly either to the double-width longitudinal folder or to the other two longitudinal folders in parallel.

27. Mechanism for folding the product of a printing press, comprising one double width longitudinal folder and two longitudinal folders of lesser width, one of said lesser width longitudinal folders being constructed and arranged so as to coöperate in series with said double width folder or in parallel with the other of said lesser width folders.

In testimony whereof, I have signed my name to this specification, in the presence of two subscribing witnesses.

GLENN S. WILLIAMSON.
